(57) **CLAIM**

The ornamental design for a ceiling fan as shown and described.

DESCRIPTION

FIG. 1 is a lowered quartering perspective view of the new design for a ceiling fan;

FIG. 2 is an elevated quartering perspective view of the design of FIG. 1;

FIG. 3 is a bottom plan view of the design of FIG. 1;

FIG. 4 is a top plan view of the design of FIG. 1;

FIG. 5 is a left side elevational view of the design of FIG. 1, the right side elevational view thereof being a mirror image of FIG. 5;

FIG. 6 is a front elevational view of the design of FIG. 1; and,

FIG. 7 is a rear elevational view of the design of FIG. 1. Broken lines included within the figures (FIGS. 2, 4) depict environmental subject matter only and form no part of the claimed design.
